UNITED STATES PATENT OFFICE.

ROBERT CHAS. COLE, OF HARTFORD, CONNECTICUT, ASSIGNOR TO THE JOHNS-PRAT COMPANY, OF HARTFORD, CONNECTICUT, A CORPORATION OF CONNECTICUT.

FUSED DISCONNECTING-SWITCH.

1,039,257.

Specification of Letters Patent. Patented Sept. 24, 1912.

Application filed April 23, 1912. Serial No. 692,652.

To all whom it may concern:

Be it known that I, ROBERT CHARLES COLE, a citizen of the United States, residing at Hartford, in the county of Hartford and State of Connecticut, have invented a new and useful Improvement in Fused Disconnecting-Switches, of which the following is a specification.

This invention relates to a switch that is particularly adapted to be used in a high tension circuit between the main lines and a transformer, although, of course, it may be used in other situations.

The object of the invention is to provide a switch for this purpose which is simple and cheap to manufacture, convenient and safe to operate, and which is readily fused in such manner as to protect the circuit, the fuse being thoroughly shielded from the weather.

Figure 1 of the accompanying drawings is a view looking at the front of the device, with a portion of the fuse and its housing broken away. Fig. 2 shows a side elevation with the fuse housing and a portion of one of the insulators cut in central section in order to show the construction.

The base 1 is desirably made in the form of a yoke of galvanized malleable iron with perforations 2 for the fastening bolts or lag screws used to secure the base in place. The out-turned ends of the base are in the shape of ribbed pins 3, and cemented or otherwise firmly fastened on these are insulators 4. These insulators are preferably made of porcelain, in such form as to afford high electrical protection and have sufficient strength, although of course the insulators could be made of other suitable insulating material or compound.

Cemented or otherwise securely fastened in recesses in the front of the insulators are ribbed pins 5. Attached to these pins are contact lugs 6, which are designed to be connected with the line and transformer wires. The outer ends of these pins are shaped to form contact plates 7.

Pivoted to the contact plates at the outer end of the lower insulator pin, by the bolt 8 upon which turns the wing nut 9, is the terminal blade 10 that is integral with the cap 11 which supports and closes the lower end of the fuse housing 12. This housing may be made of a fiber, or porcelain, or other insulating tube, and its lower end is

securely held in the cap at the bottom by the screws 13. Vent holes 14 may be made through the bottom of this lower cap if desired. Encircling the upper end of the housing is a metallic band 15, which is securely fastened to the housing by screws 16, and which is provided with an eye 17. Pivoted to one side of this band is a metallic cover 18, projecting upwardly from which is the integral terminal blade 19 that is designed to pass into and out of the contact plates at the outer end of the upper insulator pin. The cover is normally retained closed by means of the catch spring 20, which is shown as fastened to the band at the upper end of the housing.

The cartridge fuse 21 is placed in the housing with its lower terminal 22 resting on the boss 23 on the inside of the cap at the bottom of the housing, and when the cover is closed, the upper terminal 24 of the fuse is engaged and held in place by the arms of the spring 25 which is fastened to the boss 26 on the inside of the cover.

The housing, which is pivoted at its lower end to the contact plates projecting from the bottom insulator pin, by the removable bolt that is held in place by the wing nut, can be readily swung out and down for opening the circuit, by engaging a hook, at the end of an insulating handle, with the eye at the upper end of the housing, and it can be swung back by the same means so that the upper blade will engage the contact plates that project from the top insulator pin for closing the circuit. When it is desired to re-fuse the device, after the housing has been swung down for opening the circuit and the latch spring is released the cover swings open and the fuse in the housing drops out.

After a new fuse is placed in the housing, the cover is closed and the housing swung back to close the circuit. This structure is efficiently insulated and can be safely manipulated, even when used in a high tension circuit. Fuse protection is provided, the fuse is accessible, and it is a simple and safe operation to remove a blown fuse and substitute a fresh one. The fuse is handled when the circuit is opened, and it is thoroughly protected from the weather when the circuit is closed.

The invention claimed is:

1. A fused switch having a base, insulators mounted on the base, contacts carried by

the insulators, and a housing of insulating material that is closed at both ends, one closed end being pivoted to the contact carried by one insulator and the other end being closed by a removable cap that is adapted to be swung into and out of engagement with the contact on the other insulator.

2. A fused switch having a yoke-shaped base with insulators mounted on the ends of the yoke, pins with contacts projecting from the insulators, a housing with one end pivoted to one contact and the other end adapted to swing into and out of engagement with the other contact, a cover adapted to open and close one end of the housing, and a fuse removably retained in the housing by the cover.

3. A fused switch having a base, insulators mounted on the base, contacts carried by the insulators, a cap pivoted to one contact, a tubular housing fastened to the cap, a cover hinged to the other end of the housing and having a part adapted to engage the other contact, and a fuse removably located in the housing and having one terminal in electrical engagement with the cap and the other terminal in electrical engagement with the cover.

4. A fused switch having a base, insulators mounted on the base, contacts projecting from the insulators, a cap pivoted to one

contact, a housing secured to the cap, a cover hinged to the other end of the housing and adapted to be engaged with and disengaged from the other contact, a spring projecting into the housing from the cover, and a fuse with one terminal engaging the cap and the other terminal engaging and held by the spring on the cover.

5. A fused switch having a yoke-shaped base with insulators mounted on the ends of the base, pins projecting from the insulators, said pins having contact plates at their outer ends, a cap removably hinged to one contact, an insulating tubular housing secured to the cap, a band encircling the other end of the housing, a cover hinged to the band, a blade projecting from the cover and adapted to be engaged with and disengaged from the contact carried by the other insulator, a fuse removably located in the housing and having one terminal electrically connected with the cap and the other terminal electrically connected with the cover, means connected with the band for holding the cover closed, and means for swinging the free end of the housing from its contact plates.
